UNITED STATES PATENT OFFICE.

WENZEL STEPHEN, OF ST. LOUIS, MISSOURI.

SKITTLE-TABLE.

SPECIFICATION forming part of Letters Patent No. 611,398, dated September 27, 1898.

Application filed January 3, 1898. Serial No. 665,407. (No model.)

To all whom it may concern:

Be it known that I, WENZEL STEPHEN, a citizen of the United States, residing at St. Louis, State of Missouri, have invented certain new and useful Improvements in Skittle-Tables, of which the following is a full, clear, and exact description, reference being had to the accompanying drawings, forming a part hereof.

10 My invention has relation to improvements in skittle-tables; and it consists in the novel construction of table to be more fully set forth in the specification and pointed out in the claim.

15 In the drawings, Figure 1 is a top plan view of the table. Fig. 2 is a vertical longitudinal section on line 2 2 of Fig. 1. Fig. 3 is a horizontal section on line 3 3 of Fig. 2. Fig. 4 is a transverse section on line 4 4 of Fig. 1, and 20 Fig. 5 is a front end view.

The object of my invention is to construct a table for playing the game of ninepins, the latter being tripped or knocked down by a billiard-ball initially impelled through a 25 conduit or tubeway by a cue and then as it emerges from the conduit being properly deflected toward the ninepins set up at the upper end of the table. In detail the invention may be described as follows:

30 Referring to the drawings, 1 represents a preferably oblong table or board bounded on its longitudinal sides and at the end by a conduit or tubeway the walls of which are raised a suitable distance above the plane of the table to prevent the ninepins and the ball from rolling off the table. The conduit is composed of the longitudinal sections 2' 35 and the curved or substantially semicircular connecting-section 2" and is substantially 40 square in cross-section. The front or open end of the section 2 terminates at a point adjacent to the front edge of the table, said open end being in advance of the open end of section 2'. The open end of the section 2' 45 is inclined to the general longitudinal axis of the conduit, the outer edge of said inclined end forming a continuation of a curved wall 3, whose inner vertical face is a continuation of the inner surface of the outer wall of the 50 conduit-section 2'. The vertical inner face of the wall 3 approaches the front edge of the table, thence terminates in an inner project-

ing arm 4, whose inner face is provided with a cushioning-strip of rubber 5, the position of said arm and cushioning-strip being such 55 that the axis of the ball 6 when resting against the strip is substantially in line with the middle longitudinal line of the table, or that line along which are stationed the first and last of the row of ninepins 7 placed at 60 the upper end of the table. In front of the open end of the section 2 and disposed parallel to the front edge of the table and between the continuation of the outer wall of 65 said section and the adjacent vertical wall of the arm 4 is a ledge or strip 8, against which either the cue 9 or the hand of the operator can be rested, said ledge further serving to prevent the accidental rolling off of the billiard-ball. The arrows fully indicate the 70 path described by the ball, and the result of the game greatly depends on the impetus originally imparted to said ball, since it is on this impetus that the amount of deflection of the ball striking the cushioning-strip 5 depends. As best seen in Figs. 1 and 3, the 75 end of the inner wall of the section 2' is beveled toward the table at 10, so that the ball, should it happen to hug the inner surface of said wall as it is running through the conduit, 80 may be better guided against the curved wall 3. This construction prevents the ricochetting of the ball at the mouth of the conduit, thereby insuring free clearance of the ball at that 85 point as it is being discharged in the direction of and impinges against the curved wall 3. Should the ball accidentally stop in the conduit by reason of insufficient impetus given thereto by the player, a second ball must be used to drive the other one out. 90 The results of the game are restricted, however, to the number of ninepins knocked down by a single ball.

The upper or cue-supporting surface of the strip 8 is in a plane below the upper wall of 95 the conduit, thereby enabling the player to strike the ball squarely—that is to say, in a line parallel to the direction in which the ball is to be impelled. It is for this reason that the cushion of the table is omitted in front of 100 the strip.

Having described my invention, what I claim is—

In a skittle-table, a suitable oblong nine-

pin-supporting board, a conduit or tubeway bounding two longitudinal sides and the rear curved end of the board, and having walls raised above the plane thereof, the open end 5 of one of the longitudinal sides or sections of the conduit being in advance of the opposite side or section, a curved wall forming a continuation of the inner surface of the outer wall of said opposite section, the open end of 10 said opposite section being inclined to the plane of the outer wall thereof to prevent ricochetting of the ball at that point, an inwardly-projecting arm forming a continuation of said curved wall, a cushioning-strip 15 against which the ball impinges carried by said arm, the deflecting-surface of said strip being to one side of the medial longitudinal line of the board a distance approximately equal to the radius of the play-ball, whereby

the axis of said ball when resting against said strip is in line with said longitudinal line of the board, and a ledge or strip located adjacent to the open end of one of the longitudinal sides of the conduit interposed between the arm and the adjacent side of the table 25 for the support of the hand and cue, the supporting-surface of the strip being below the plane of the upper wall of the conduit, whereby the cue can be directed against the ball in a plane substantially parallel to the bed of 30 the table, substantially as set forth.

In testimony whereof I affix my signature in presence of two witnesses.

WENZEL STEPHEN.
